UNITED STATES PATENT OFFICE.

ALDEN L. HOWARD, OF ANN ARBOR, MICHIGAN.

AUTOMATIC STARTING AND STOPPING DEVICE FOR PHONOGRAHS.

Application filed November 4, 1921, Serial No. 512,908. Renewed July 27, 1925.

To all whom it may concern:

Be it known that I, ALDEN L. HOWARD, a citizen of the United States, residing in the city of Ann Arbor, county of Washtenaw, 5 and State of Michigan, have invented certain new and useful Improvements in Automatic Starting and Stopping Devices for Phonographs, of which the following is a specification.

10 This invention relates particularly to an automatic starting and stopping mechanism for the disk type of phonograph.

15 Among the salient objects of the invention are to provide a device or attachment which automatically starts the machine when the tone arm is moved to a position where the needle may be placed upon the beginning of the record and which, when the tone arm has moved across the record 20 and the selection has been completed, the mechanism will automatically stop the rotation of the disk; to provide a device which is simple in operation, relying solely on the movement of the tone arm for its control of 25 the disk and upon mechanism controlled by the motor which rotates the disk which automatically brakes the motor mechanism at predetermined positions of the tone arm; to provide a mechanism which is positive in its 30 operation and is not affected by slight eccentricities of the disk.

In the drawings:

Fig. 1 is a plan view of the mechanism with the disk of the machine broken away 35 to show its operation.

Fig. 2 is a plan view of a modified form of construction.

Fig. 3 is a side view of the mechanism shown in Fig. 2.

40 Fig. 4 is a detail of the clutch mechanism in the wheel which contacts the sector in Figs. 2 and 3.

Fig. 5 is a sectional view of the clutch wheel shown in Fig. 4.

45 Referring in detail to the drawings, as shown in Fig. 1, the drums 1 enclosing the spring, drive the gear 2, which meshes with a worm 3, which in turn drives the gear 4 and the worm 5 mounted on a shaft 6 which 50 is provided with a governor device 7 and a disk wheel 8 contacted by the braking pad 9, as will hereinafter be more fully explained. The gear 2 also meshes with a gear 10 mounted on the shaft 11, upon which is also 55 mounted a worm gear 12, driving the gear 13 through the worm gear 14, both of which

are mounted on the vertical shaft 15. The tone arm 16 is fitted with a curved portion 17 upon which fits sound box 18. This tone arm is pivoted at 19 and moves horizontally 60 across the disk of the record during the playing of a selection.

On the tone arm 16 is a pin 20 which fits into curved slot 21 in an elongated arm 22, which is pivoted at 23. A second arm 25 65 also pivoted at 23 in a slotted hole 24 has a sector 26 which is toothed and on being moved across with the movement of the tone arm meshes with the gear 13 on the vertical shaft 15. In the lower arm is also cut an 70 L-slot 27 into which fits a square pin 28 extending downwardly from the upper arm 22. Near the pivoted extremity of the arm 25 is a curved slot 29 which is fitted by a finger 30 which is an upturned end of the 75 connecting rod 31. On the opposite end of this rod is fixed the pad 9 which contacts the disk 8 in stopping the motor. A spring 32 is fastened to the rod and imposes a constant tension upon the rod 31 and the arms 80 25 and 22 tending to pull the pad 9 to contact the disk 8. In operation, the mechanism functions as follows:

When the tone arm is moved from a position outside the playing area of the record 85 (at which time the brake is applied as the arm 25 is at its extreme right position and the pin 28 is near the left end of the slot 27) to the playing area, the pin 33 rides up the incline of the part 34, thus moving 90 arm 25 to the left which releases the brake and the disc begins to revolve.

When the machine is started and the disk commences to rotate, the needle 35 on the sound box 18 may be placed in the initial 95 grooves of the record, and as it continues to move across the surface of the record, the arms 22 and 25 are each pivoted at 23 and will likewise move with it, the pin 20 advancing along the curved slot 21 in the 100 arm 22.

Further movement of the tone arm causes the pin 28 on arm 22 to move on the lateral part of the slot 27 and this relation exists until the end of the selection.

Upon backward movement of the tone arm the pin 28 rests in the corner of the slot 27 and cannot occupy the left end of said slot as the pin 33 engages the part 34 and prevents spring 32 from acting. Upon 110 completing the backward movement of the tone arm, that is, when the needle is beyond

the playing area of the record, the pin 33 rides down the incline of the cam 34 thus allowing the spring 32 to act and the arm 25 now moves to its starting position, that is so that the pin 28 occupies a position near the extreme left end of the slot 27.

It will be noted, however, that during this return movement until the pin 33 rides down the incline of the cam 34 the arm 25 is held away from its extreme right position or braking position, and the record may revolve. The time necessary to move the tone arm across the record being so short, however, the record turntable will not revolve appreciably, particularly because as soon as the tone arm has been moved beyond the playing area the brake will be applied as described above. If therefore, it is desired to repeat the selection, or a new selection has been placed on the turntable, the tone arm need not be moved to a position beyond the playing area and playing may be begun immediately as the record will already be revolving.

In the modified form of construction, the operation of the mechanism is very similar to that shown in Fig. 1, the only difference being that the braking of the governor is effected in the same manner but through connections different from those shown in Fig. 1. The tone arm 16 is similarly equipped with curved portions 17 which carries the sound box 18 and is pivoted at 19 to move horizontally across the surface of the record. An arm 36 is pivoted at 37 to the tone arm 16 and has a turned down portion which protrudes in the shape of a pin 38 through the arms 39 and 40. These arms function similarly to the arms 25 and 22 shown in Fig. 1. The arm 40 is pivoted at 41 by slotted holder 42 extending longitudinally of this lower arm. On the end opposite the pivot is formed a sector 43, which contacts with the clutch wheel 44 when the tone arm has moved across the surface of the record to a position approaching the end of the selection. This sector portion has an L-slot 45 into which fits a depending stud or pin 46 from the arm 39. The arm 39 is pivoted below the top surface plate 47 of the machine and is so formed that it rises through the surface plate through the slot 48 extending from this slot to its extremity above the surface plate of the machine. The arm 40 on the other hand, is positioned below the surface plate of the machine for substantially its entire length being bent near its extremity upon which the sector is mounted so that the sector containing the L-slot is positioned above the surface plate of the machine to contact with the clutch wheel as explained. The arm 40 is bent to rise through the surface plate through the cam slot 49. The arm 40 has a second upstanding stud 50 which con-

tacts the edge of the cam slot as shown at 51 when the tone arm is moved to the right so that the pin 46 which is moved into the corner of the L-slot 45 will be pushed up into the longitudinal leg of the L-slot and through this action through a series of connections hereinafter explained causes the disk to rotate.

Briefly explaining the motor mechanism, two springs 52 encased in drums drive the large gears 53, which in turn through the worm 54 and gear 55 mounted on shaft 56 drive the vertical spindle 57 through the gear 58. The spindle 57 supports the disk 59 which carries the record 60. Mounted also on the spindle 57 is a worm gear 61 driving the worm 62 mounted on a shaft 63. Upon this latter shaft is also mounted a governor 64 which is contacted by the stop or brake pad 65 on the bell crank 66 pivoted on the shaft 67. The upper leg of this bell crank is connected through the link connection 68 to the lower arm 40 by an upturned pin 69 which fits in the slot 70. A spring 71 imposes a tension upon the link and its connections so when the arm 40 is released to slide along the pivot 41 in the slot 42, the spring will shift the link 68 to cause the pad 65 to contact the governor mechanism and stop the machine. Meshing with one of the gears 53 is a small gear 72 mounted on the shaft 73. This shaft drives the worm 74 mounted thereon which in turn meshes with a gear 75 mounted on a shaft 76, upon which the clutch wheel 44 is also mounted. This clutch wheel has an upper hollowed portion into which are fitted pivot members 77, held in position by flat springs 78 which permit the clutch wheel to rotate in the direction shown by the arrow but assures the clutch wheel being fixedly connected with the shaft 76 when the clutch wheel is moved with the sector in its travel during the playing of a selection. The operation of the clutch wheel is such that when driven by the worm or moving with the sector, the wheel 44 moves as a unit with the shaft 76. When the tone arm is moved across the record to a starting position, the sectors 43, contacting with the clutch wheel 44, will rotate the wheel in a direction opposed to that shown by the arrows, at which time the wheel turns freely upon the shaft 76.

The operation of the device is as follows. When the tone arm is moved to the edge of the disk or record, when a selection is to be started, the arm 36 will move the pivot arms 39 and 40 with the tone arm. As the upper pivot arm 39 is swung with the tone arm, the pin 46 will move into the corner of the L-slot, 45. In this position, the spring 71 takes effect, sliding the lower arm 40 longitudinally in this slot 42, causing the pin 46 on the end of the upper arm to slide into

the longitudinal leg of the L-slot 45. The taking effect of the spring and the releasing of the lower arm causes the link 68 to slide with the arm, stopping the disk through the 5 braking mechanism as explained. When the tone arm has been moved to the extreme position or to a position for starting, the pin 50 has moved along the opposite side of the cam slot at 79 moving the pin 46 10 into the corner of the L-slot, thus sliding the lower arm longitudinally of the slot 42 against the spring tension 71, which movement releases the braking pad from the governor, permitting the disk to rotate. 15 With the movement of the tone arm to the right across the surface of the record, the pin 46 is supported in the transverse leg of the L-slot 45 and ride upon the angular shoulder 80 formed in the corner of the L- 20 slot shown in Fig. 2.

The extent of this shoulder is limited by the adjusting screw 81. In its travel across the surface of the disk, the tone arm will carry with it two arms 39 and 40 due to 25 their connection with the tone arm through the pivoted arm 36.

When the needle has progressed to a position approaching the end of the selection, the sector 43 will contact with the surface of 30 the clutch wheel 44 and the latter being geared to rotate at substantially the speed at which the sector is travelling will move with it. When the needle has progressed to the end of the record, its horizontal movement is checked due to the fact that it has 35 reached the final playing groove. Here, the horizontal movement of the tone arm is checked but the clutch wheel, due to its connection with the driving mechanism continues, carrying with it the sector due to 40 its contacting relation with the sector. As the sector progresses with the clutch wheel, the upper arm 39 due to its connection with the tone arm is stopped and the pin 46 is 45 moved off of the shoulder 80, permitting the spring 71 to take the effect and slide the lower arm longitudinally to brake the mechanism and stop the rotation of the disk. The adjustment may be made so accurately 50 that almost immediately with the reaching of the final groove by the needle fixed in the sound box, the mechanism will be stopped in the manner explained.

To the shaft 67 upon which the bell crank 55 66 is pivoted, is also fixed an upright pin 82, which is contacted by a stopping mechanism 83. When the stopping mechanism is rotated to an automatic position, the pin 82 is free to move with the shaft 67 but 60 when the stop is placed in a non-automatic position, the mechanism will assume the position shown in full lines in Fig. 3 and prevent the actuation of the automatic stop due to its contact with the vertical pin 82. 65 When the starting and stopping mecha-

nism is operating automatically with the movement of the tone arm to the extreme right, the motor will be stopped by means of the braking of the governor. With the movement to the left to the starting position, when the stud 50 rides along the edge designated as 79 of the cam slot, the motor will be started due to the releasing of the braking mechanism. The rotation of the disk will continue until the pin 46 is moved from the shoulder 80 by the checking of the forward movement of the sector, and continued rotation of the clutch wheel. Within the tone arm support 84 is a post 85, about which is coiled a spring 86, fastened at its upper end to the pin 87 fixed to the cross bar 88 in the tone arm. This spring imposes a slight forward rotating tension upon the tone arm assisting in the movement of the tone arm across the record in the applying of a selection. The function of this spring is to assist the movement of the tone arm due to the fact that in reproduction of some records, a blunt needle is used which does not easily follow the grooves of the record unless 90 the tone arm moves very freely. In most records, where a sharp needle is used in a comparatively deep groove, the tone arm will readily follow the movement of the sound box, but if the grooves of the record are comparatively shallow and the needle blunt, a construction used with some manufacturers, it is necessary that the tone arm move freely in order that its horizontal progression across the record is not checked until the end of the selection has been reached. If, for any reason, the horizontal movement of the tone arm is checked during the playing of a selection, the rotation of the disk will be immediately stopped due to the dropping of the pin 46 from the shoulder 80. 100

In the construction shown in Fig. 1, where the sector is toothed to mesh with the gear 13, the sector is pivoted and a small spring connected thereto to hold the sector in a position to mesh properly when the sector is moved in its travel to a position to mesh with the gear or should the teeth of the sector and gear not be in proper position for meshing the sector will give slightly on its pivot receding from the gear so that a proper meshing will be effected. The mechanism here shown is adaptable to any type or disk machine and although being sensitive to the movement of the record in its ability to stop and start the driving mechanism, it is rugged in design so that adjustment is not easily effected by rough usage. 110 115

I claim as my invention:

1. In an automatic starting and stopping device for phonographs, the combination with a rotating disk, a reproducing mechanism mounted on an arm adapted to progress across said disk, of pivoted mechanism 120 125 130

moving with the arm in timed relation with the rotation of the disk whereby the movement of the reproducing mechanism across the disk functions to start and stop the 5 rotation of the disk at predetermined times.

2. In an automatical starting and stopping device for phonographs, the combination with a rotating disk, a reproducing mechanism mounted on a tone arm adapted 10 to move across the disk, elongated arms adapted to move with the reproducing mechanism and in timed relation with the rotating mechanism operable to start and stop the mechanism at predetermined positions of the 15 tone arm.

3. In an automatic starting and stopping device for phonographs, the combination with a rotating disk, of reproducing mechanism mounted on a tone arm and adapted 20 to move therewith across the disk, pivoted arms connected to the tone arm, a disk rotating mechanism operable to start the rotation of the disk when the reproducing mechanism is in a position at the beginning of a selection and to stop the rotation of the disk at 25 the end of the selection.

4. In an automatic starting and stopping device for phonographs, the combination with a reproducing mechanism operable to 30 move across a rotating disk during the playing period, elongated arms moving with the reproducing mechanism operable therewith and with the rotating mechanism to start and stop the rotating mechanism at predetermined positions of the reproducing mechanism.

5. A method of starting and stopping a phonograph having a horizontal disk for records consisting in automatically stopping 40 the revolving of the disc when the tone arm is positioned substantially at the circumference of the disk, and in automatically starting said disc when the tone arm is in a position for the needle to be placed in the starting grooves of the record and in automatically stopping the revolving of the disc 45 at the completion of the selection.

6. A method of starting and stopping a

phonograph having a horizontal disk for records consisting in automatically stopping 50 the revolving of the disk when the tone arm is moved to a position substantially at the circumference of the disk and automatically starting the rotation of the disk when the tone arm is moved to a position for the re- 55 producing mechanism to be placed in the first groove of the record, and in automatically stopping the revolving of the disk at the arrival of the reproducing mechanism at substantially the last groove of the record. 60

7. In combination, a phonograph turntable, means to rotate said turntable, a tone arm adapted to engage a record supported on said turntable, said record having a playing area and a non-playing area, reproducing mechanism carried by said tone arm and adapted to engage the playing area of said record, said turntable rotating mechanism causing said turntable to rotate only when the reproducing mechanism is within the 70 limits of the playing area, and means to prevent rotation of the turntable when the reproducing mechanism is in proximity to the extremities of the playing area, including a wedge block. 75

8. A method of starting and stopping a phonograph having a horizontal disc for records, consisting in automatically stopping the revolving of the disc when the tone arm is moved to a position beyond the playing area of the disc, and automatically starting the rotation of the disc when the tone arm is moved to a position for the reproducing mechanism to be placed in the first groove of the record, and in automatically 85 stopping the revolving of the disc at the arrival of the reproducing mechanism at substantially the last groove of the record.

9. A method of starting and stopping the driving mechanism of a phonograph, consisting in stopping ~~said~~ mechanism when the tone arm is to either side of the playing area of the record, and permitting the same to operate when the tone arm is moving over said area. 90

ALDEN L. HOWARD.
